Primary Examiner — Elizabeth A. Albert(74) *Attorney, Agent, or Firm* — Seed Intellectual Property Law Group LLP(57) **CLAIM**

The ornamental design for a pencil sharpener, as shown and described.

DESCRIPTION

FIG. 1 is a tilted view of a pencil sharpener rotated between a rear and right side elevation view showing my new design. FIG. 2 is a front elevation view thereof.

FIG. 3 is a rear elevation view thereof.

FIG. 4 is a left side elevation view thereof, with the right side elevation view being a mirror image of the left side elevation view.

FIG. 5 is a bottom plan view thereof; and,

FIG. 6 is a top plan view thereof.

1 Claim, 4 Drawing Sheets(56)
